FIREARM

Melvin M. Johnson, Jr., Brookline, Mass.

Application April 2, 1936, Serial No. 72,301

8 Claims. (Cl. 42—4)

This invention relates to firearms of the semi-automatic type having a bolt slidably mounted for a reciprocating stroke between a rearward open-breech position and a forward unlocked position, at least a portion of the bolt being rotatable from unlocked to locked position, and having means for feeding cartridges into position to be pushed into the firing chamber during the forward stroke of the bolt. The invention is especially applicable to firearms in which the bolt is locked to a reciprocating barrel and unlocked in response to or by virtue of a slight recoil of the barrel.

Objects of the invention are to provide automatic breech mechanism which has sufficient strength to function indefinitely with high-power ammunition, to facilitate the feed of cartridges to the firing chamber, to improve the locking and unlocking action of the bolt, to simplify the construction of firearms of the type referred to and generally to improve the art of semi-automatic firearms.

In one aspect the present invention involves a bolt having at its forward end a locking head provided with one or more circumferential rows of locking lugs which move in front of locking abutments when the head is rotated into locking position, the bolt having a recess behind the locking lugs to accommodate the aforesaid abutments and the radial dimensions of the bolt, at least on the side from which the cartridges are supplied, are approximately the same forwardly and rearwardly of the recess, whereby the feed of cartridges to the firing chamber is facilitated.

In another aspect the invention relates particularly to firearms of the aforesaid recoiling-barrel type, involving improved means for rotating the locking lugs into and out of locking position behind the aforesaid locking abutments which, in this aspect, are on the recoiling barrel. The rotating portion of the bolt (which preferably constitutes the entire bolt) is provided with a cam surface engageable with a cam surface on the receiver to cam the bolt from locked to unlocked position as the bolt and barrel recoil together, after which the bolt continues to move to fully retracted position in response to the residual gas pressure and to some extent its own inertia. The angularity and circumferential extent of the receiver cam, the friction of the sliding surfaces, and the inertia of the moving parts are preferably correlated so that the bolt is not fully unlocked until after the projectile has left the barrel and after the gas pressure has decreased to a safe value sufficient only to retract the bolt without

excessive force. To return the locking lugs to locked position, at the end of the forward stroke of the bolt, the rotary portion of the bolt is provided with another cam surface, engageable with a cam surface on the bolt pusher between the bolt and recoil spring, to rotate the locking lugs into locking position in front of the locking abutments on the barrel. Preferably the locking and unlocking cam surfaces on the bolt are provided on opposite sides of a lug on the bolt which slides in a slot in the receiver adapted to prevent rotation of the bolt except at the forward end of its reciprocating stroke.

For the purpose of illustration a typical embodiment of the invention is shown in the accompanying drawings in which,

Fig. 1 is a side elevation of a rifle of the Army type;

Fig. 2 is a section on line 2—2 of Fig. 1;

Fig. 3 is a section on line 3—3 of Fig. 1;

Fig. 4 is a section on line 4—4 of Fig. 2;

Fig. 5 is a section on line 5—5 of Fig. 3;

Fig. 6 is a front elevation of the bolt;

Fig. 7 is a top plan view of the bolt and pusher showing the barrel in axial section;

Fig. 8 is a similar view showing the bolt in locked position;

Fig. 9 is a bottom plan view of the barrel and receiver with parts broken away;

Fig. 10 is a section on line 10—10 of Fig. 9; and

Fig. 11 is a vertical axial section through the forward end of the receiver and stock showing the barrel in side elevation.

The particular embodiment of the invention chosen for the purpose of illustration comprises a stock having a rear butt portion 1 and a forward portion 2 extending under the receiver, a frame in the form of a receiver having a rearward portion 3 to accommodate the bolt and a forward portion 4 telescoping over the rearward end of the barrel, a barrel 5, a bolt 6 and a bolt pusher 7, the stock containing a magazine of the well-known Springfield type for feeding cartridges into position to be pushed into the firing chamber in the forward stroke of the bolt.

The barrel has a limited degree of longitudinal movement in the receiver from the forward position shown in Fig. 9 to a rearward position in which the rear end of the barrel engages the shoulder 8 on the receiver (Fig. 9). Forward movement of the barrel is limited by a sleeve 9 (Fig. 11) press-fitted on the barrel and engageable with a collar 10 threaded on the forward end of the receiver. Rotary movement of the barrel in the receiver is restrained by a depending lug 55

11 on the sleeve 9 and another lug 12 projecting downwardly from the rear end of the barrel, both lugs sliding in a slot 13 in the lower side of the receiver. The lower end of lug 11 is provided with a socket 14 to receive the forward end of a compression spring 13, the rear end of which seats against the bottom of an aligned socket in the stock 2 (Figs. 1 and 11). The rear end of the barrel is provided with a circumferential row 10 of interior locking abutments 17 with alternate grooves 18 therebetween.

The forward end of the bolt 6 is provided with corresponding exterior locking lugs 19 for engagement in front of the locking abutments 17, 15 the circumferential width of the lugs 19 approximating that of the abutments 17 and being slightly less than the width of the grooves 18 so as to pass between the abutments 17 when the bolt is rotated to unlocked position. Immediately 20 behind the locking lugs 19 the bolt is provided with an annular recess 20, the diameter of the bolt forwardly and rearwardly of this recess being approximately the same. Projecting 25 from the top of the bolt near its rearward end is a cam lug 21 adapted to slide forwardly and rearwardly in a groove 22 in the top of the receiver. At the forward end of the stroke of the cam lug 21 the receiver groove 22 is provided with a lateral recess 23 having a cam surface 24 engageable with the cam surface 25 on the lug 21 when the bolt is rotated into locking position. On the other side of the lug 21 is another cam surface 25' engageable with a cam surface 26 at the forward end of the bolt-pusher 30 er 7.

The pusher 7 is yieldingly urged forwardly by a recoil spring 27 mounted in the butt 1 of the stock and kinematically interconnected with the pusher by means of links 28. The firing pin 29 projects rearwardly through the pusher 7 as shown in Figs. 4, 5, 7, and 8 and the hammer (not shown) moves into engagement with the bolt through a slot 30 in the bottom of the receiver and thence into the space between the two links 28. The extractor 31 is integral with the bolt (Fig. 6) and the ejector (not shown) projects into a slot 32 in the opposite side of the bolt, the rearward portion 32' of the slot being widened to accommodate the rotary movement of the bolt 50 (Figs. 2 and 3). The forward ends of the locking lugs 19 are flush with the forward end of the bolt.

When the bolt is in locked position (Figs. 1, 3, 5, and 8) the locking lugs 19 are in front of the locking abutments 17, thereby preventing endwise movement of the bolt relatively to the barrel, and the cam lug 21 is in the recess 23 in the side of the receiver groove 22 as shown in Figs. 3 and 5. When the cartridge is fired the barrel 60 and bolt recoil together and during this recoil movement the bolt is rotated to unlocked position by interengagement between the surfaces 24 and 25 of the receiver recess 23 and the cam lug 21 on the bolt. By this time the projectile has 65 left the barrel and the breech pressure has dropped to a value which is little more than sufficient to retract the bolt to the rearward end of the receiver against the action of the recoil spring 27. During the backward and forward movement 70 of the bolt it is restrained from rotation by the lug 21 in the receiver groove 22. As the bolt returns to its forward position it picks up a cartridge from the magazine (not shown because it is wholly within the stock) and when it reaches 75 forward position the pusher 7 cams the bolt into

locking position by virtue of the interengagement between the cam surfaces 25' and 26 on the lug 21 and the pusher 7 respectively. During the rearward and forward stroke of the bolt the barrel is returned to its forward position by the spring 15. By making the diameters of the bolt on opposite sides of the annular recess 20 substantially equal, the uppermost cartridge in the magazine is maintained in proper alignment for feeding to the firing chamber substantially as it would if the bolt were cylindrical throughout its entire length.

It should be understood that the present disclosure is for the purpose of illustration only and that this invention includes all modifications and equivalents which fall within the scope of the appended claims.

I claim:

1. A firearm comprising in combination a barrel mounted to slide longitudinally to a slight extent in response to recoil, stop means to limit recoil of the barrel, a bolt coaxial with the barrel and also mounted to slide in response to recoil but to an extent sufficient to permit introduction of a cartridge between the forward end of the bolt and the rear end of the barrel, the bolt being provided at its forward portion with a circumferentially extending row of spaced locking lugs, at least the forward portion of the bolt being rotatable to a predetermined extent, means preventing such rotation except when the bolt is adjacent to firing position, a row of locking abutments on the barrel normally disposed to the rear of and engaging the locking lugs on the bolt thereby to lock the barrel and bolt against relative longitudinal movement, the engaging surfaces of the lugs and abutments being substantially perpendicular to the axis of the barrel, concealed unlocking means including complementary cams operative, during and in response to the short recoil movement of the barrel, to rotate at least the head portion of the bolt sufficiently to disengage the locking lugs of the bolt from those of the barrel thereby to permit the continued recoil movement of the bolt alone to breech-opening position after the recoil movement of the barrel has ceased, the barrel being free to return to firing position immediately after it is unlocked from the bolt, a recoil spring, a pusher actuatable by the spring, at the completion of the recoil movement of the bolt, to advance the bolt to breech-closing position, and relocking means, including complementary relatively movable rigid cams, one of which is carried by the pusher and advances with the latter in response to the action of the recoil spring, said unlocking means operating automatically as the bolt comes to rest at its extreme forward position to rotate at least the forward portion of the bolt and thereby to reengage the locking lugs and abutments.

2. A firearm comprising in combination a frame and a barrel mounted to slide axially therein for a slight distance in response to recoil energy, means limiting recoil movement of the barrel, a reciprocable breech-opening and closing bolt coaxial with the barrel, said bolt being rotatable to a predetermined angular extent when the bolt is adjacent to firing position, the forward portion of the bolt being provided with a circumferential row of locking lugs with intervening grooves, the rear end of the barrel having an axial bore of a diameter such as to receive the forward end of the bolt, a row of spaced locking abutments projecting inwardly from the wall of said bore and normally disposed to the rear of and engaging the locking lugs of the bolt, the engaging surfaces

of the lugs and abutments being substantially perpendicular to the axis of the barrel thereby positively to prevent relative longitudinal movement of the bolt and barrel, a cam carried by the bolt and a cooperating fixed cam concealed within the frame operative, during the short recoil movement of the barrel, to rotate the bolt thereby to disengage its locking lugs from the abutments of the barrel and permit breech-opening movement of the bolt after the recoil movement of the barrel has ceased, the barrel being free to return to firing position immediately after the bolt has been unlocked from it, a recoil spring and pusher means actuated thereby and operative at the completion of the breech-opening movement of the bolt to return the latter to breech-closing position, and a second cam on the bolt and a complementary cam carried by the pusher means operative, after the bolt reaches breech-closing position, to rotate the bolt thereby to reengage the locking lugs of the bolt with the abutments of the barrel.

3. In a firearm of the kind wherein a barrel and a coaxial breech block are mounted to slide forwardly and rearwardly in guides in a supporting frame in response to recoil energy, the barrel being arranged to slide to a slight extent concomitantly with the bolt and then to stop while the bolt continues its recoil movement to cartridge-ejecting and receiving position, means to prevent rotation of the barrel, the bolt being rotatable to a predetermined degree, a reciprocating bolt pusher, and a recoil spring urging said pusher forwardly, in combination normally contacting surfaces on the barrel and bolt respectively, said surfaces being substantially perpendicular to the axis of the barrel, for interlocking the two parts against relative endwise movement when the bolt is in the firing position, a cam lug on the bolt having two cam surfaces, a fixed cam on the frame cooperable with one of the cam surfaces of the bolt to turn the bolt from locked to unlocked position in response to the aforesaid slight rearward recoil movement of the barrel in the frame, a cam on said pusher cooperable with the other cam surface of the bolt, after the bolt has completed its axial advance to firing position, to turn the bolt from unlocked to locked position, and a spring operative to return the barrel to its forward position immediately upon release of the bolt from the barrel.

4. In a firearm of the kind wherein a barrel and a coaxially arranged breech block are mounted to recoil rearwardly in guides in a supporting frame in response to recoil energy, the barrel being arranged to slide to a slight extent concomitantly with the bolt and then to stop, and having provision for returning the barrel immediately to firing position while the bolt continues its recoil movement thereby to open the breech for the ejection and reception of cartridges, means to prevent rotation of the barrel, the forward portion at least of the bolt being rotatable to a predetermined degree but only while the bolt is adjacent to firing position, a reciprocating bolt pusher, and a recoil spring urging the pusher forwardly, in combination interengaging projections on the barrel and bolt respectively for interlocking the barrel and bolt against relative endwise movement when the bolt is in firing position, said interengaging projections having their contacting surfaces disposed substantially perpendicular to the axis of the barrel, a rigid cam surface on the frame, an element on the bolt with which said cam surface cooperates to turn said forward por-

tion at least of the bolt from locked to unlocked position in response to the aforesaid slight rearward movement of the barrel in the frame, a rigid cam surface on the pusher, and a part on the bolt with which said latter cam surface cooperates, in response to the advance of the pusher by the recoil spring, to turn said forward portion at least of the bolt from unlocked to locked position after the bolt has arrived at the extreme forward end of its path of movement.

5. In a firearm of the kind wherein a barrel and a coaxially arranged breech block are mounted to recoil rearwardly in guides in a supporting frame in response to breech pressure, the barrel being arranged to slide to a slight extent only concomitantly with the bolt and then to stop, and having provision for restoring the barrel immediately to firing position while the bolt completes its recoil movement thereby to open the breech for the ejection and reception of cartridges, means to prevent rotation of the barrel, the forward portion at least of the bolt being rotatable to a predetermined degree but only while the bolt is adjacent to the firing position, a reciprocating bolt pusher, and a recoil spring urging said pusher forwardly, in combination a radial row of locking lugs on said forward portion of the bolt which lock the bolt to the barrel in firing position, a radial row of locking abutments carried by the barrel, a recess in the bolt behind said lugs to accommodate the locking abutments, a cam carried by the bolt, a cam surface fixed relatively to the frame and cooperable with the cam on the bolt to turn said forward portion at least of the bolt from locking to unlocked position during said slight rearward movement of the barrel in the frame, a second cam carried by the bolt, and a cam surface on the pusher cooperable with said second cam on the bolt to turn said forward portion at least of the bolt from unlocked to locking position in response to the action of said recoil spring while the barrel and bolt are both in extreme forward position.

6. In a firearm of the kind wherein a barrel and a coaxially arranged breech block are mounted to recoil rearwardly in guides in a supporting frame in response to breech pressure, the barrel being arranged to slide to a slight extent only concomitantly with the bolt and then to stop, and having provision for restoring the barrel immediately to firing position while the bolt completes its recoil movement thereby to open the breech for the ejection and reception of cartridges, means to prevent rotation of the barrel, the forward portion at least of the bolt being rotatable to a predetermined degree, means operative to prevent rotation of the bolt except when it is adjacent to the firing position, a bolt pusher, and a recoil spring urging said bolt pusher forwardly, in combination, locking lugs on the forward portion of the bolt, said lugs having rear surfaces in a plane substantially perpendicular to the axis of the bolt, locking abutments carried by the barrel and which have forward surfaces in a plane substantially perpendicular to the axis of the barrel and which engage the aforesaid rear surfaces of said lugs when the bolt is in firing position, the bolt having a recess behind said lugs to accommodate said abutments and being or approximately the same diameter forwardly and rearwardly of said recess, thereby to facilitate the feed of cartridges to the firing chamber, bolt unlocking means and bolt relocking means concealed within the frame, the unlocking

means including cam elements, one carried by the bolt and the other by the frame, operative automatically to turn the bolt and thereby to unlock it from the barrel during and in response to the short recoil movement of the barrel, the relocking means including cam elements, one carried by the pusher and one by the bolt, operative in response to advance of the pusher by the recoil spring to turn the bolt back to relock it to the barrel after the barrel has been fully advanced to firing position.

7. In a firearm of the kind wherein a barrel and a coaxially arranged unitary breech block are mounted to recoil rearwardly in guides in a supporting frame in response to breech pressure, the barrel being arranged to slide to a slight extent only concomitantly with the bolt and then to stop, and having provision for restoring the barrel immediately to firing position while the bolt completes its recoil movement thereby to open the breech for the ejection and reception of cartridges, means to prevent rotation of the barrel, the bolt being rotatable to a predetermined degree but only while adjacent to firing position, a reciprocating bolt pusher, and a recoil spring normally urging said pusher forwardly, in combination a radial row of locking lugs on the forward portion of the bolt, a radial row of locking abutments carried by the barrel and which engage rear surfaces of said lugs when the bolt is in firing position, the bolt having a circumferentially extending recess behind said lugs to accommodate the abutments, the portions of the bolt at opposite sides of the recess being of substantially the same diameter and cross section thereby to facilitate the delivery of cartridges into the firing chamber, bolt locking means and bolt unlocking means concealed within the frame, the unlocking means comprising rigid, relatively movable elements, cooperable in response to recoil energy, to rotate the bolt thereby automatically to disengage the locking lugs from the abutments during the short recoil of the barrel, the locking means including cooperating relatively movable cams, operative in response to advance movement of the pusher and, after the bolt has been advanced to firing position, to turn the bolt and thereby to reengage its locking lugs with the locking abutments of the barrel.

8. In a firearm of the kind comprising a frame, a barrel mounted to slide axially to a slight extent only in the frame, a breech bolt coaxial with the barrel and mounted to slide rearwardly in the frame to a much greater extent than the barrel from firing position to cartridge-ejecting and receiving position, the bolt also being rotatable to a predetermined angular extent but only when it is adjacent to the firing position, in combination locking means normally uniting the bolt and barrel, said locking means comprising a radial row of locking lugs on the forward portion of the bolt, a radial row of locking abutments carried by the barrel engaging the rear surfaces of the lugs when the bolt is in firing position, and means for automatically unlocking and retracting the bolt in response to recoil energy, said unlocking means comprising a cam surface on the bolt and a fixed cam carried by the frame, said cams being designed and arranged to rotate the bolt during the short concomitant recoil movement of the bolt and barrel thereby to disengage the lugs and abutments and allow axial separation of the bolt from the barrel, means to restore the barrel to firing position immediately after it is released from the bolt, a pusher for restoring the bolt to firing position, and relocking means comprising a second cam surface on the bolt and a cam carried by the pusher cooperative therewith to turn the bolt back to locking position after it has completed its return movement to firing position.

MELVIN M. JOHNSON, JR.
